MORIS M. BERGER, OF CLEVELAND HEIGHTS, OHIO, ASSIGNOR TO DORIS P. BERGER,
OF CLEVELAND HEIGHTS, OHIO.

SPRING MOTOR FOR CLEANING APPARATUS.

Application filed February 8, 1922. Serial No. 535,071.

To all whom it may concern:

Be it known that I, MORIS M. BERGER, a citizen of the United States, and a resident of Cleveland Heights, county of Cuyahoga, and State of Ohio, have invented a new and useful Spring Motor for Cleaning Apparatus, of which the following is a specification.

My invention relates to spring motor for cleaning devices whereby a brush, or other wiper, or other means, is operated over a surface to be cleaned.

The main objects of my invention are an efficient device for operating a cleaning apparatus, which device is light in weight, which eliminates high friction mechanisms, which is simplified to reduce the cost of production, in which all of the parts thereof are easily accessible and without disturbing other parts thereof, in which the speed of power discharge is controlled, which can readily be stopped and started, and in which the stop and start mechanism is automatically retained either in the stop or in the start position without any auxiliary locking means.

In many instances, as in automobile windshields, or in locomotive cabs, or in street-car vestibules, as well as in numerous other instances, it is necessary, or at least desirable, that the windows be cleaned in case of a storm, either rain or dust storm, so that the operator or driver may be able to see what is ahead and avoid accidents.

Hand operated devices for such purposes are dangerous since the operator must release some of his attention from the control mechanism of his vehicle and apply it to the operation of the hand cleaning device; whereas the full and undivided attention of the operator should be directed toward the control of the vehicle, particularly in a storm at which time the hand operated cleaner must also be operated.

An apparatus which embodies the features of the present invention and eliminates manual operation is shown in the accompanying drawing in which Fig. 1 is a general perspective view of a spring motor and a windshield cleaner connected therewith, and Fig. 2 is an end view at 2 of Fig. 1. Smiliar reference characters refer to similar parts throughout the views.

The spring motor shown in the drawing

has a general housing composed of the rear wall 10, the front wall 11, the subwall 12, and the spacers 13, 14, 15, and 16.

The walls 10, 11, and 12 are made of suitable material, are sufficiently cut away to reduce weight, and are provided with the necessary journals and other openings as will appear presently.

The rear wall 10 is suitably spaced from the front wall 11 by the spacers 14, 15, and 16, all of which are provided with threaded ends and nuts 17, on each end, whereby these two walls are firmly held in proper relation to each other.

The sub-wall 12 is located some distance inside of the front wall 11 and is firmly held in proper relation to the walls 10 and 11 by the spacers 13 and 15 and the nuts 17 thereon.

The power shaft 18 is journaled in the walls 10 and 11 and has collar 19 bearing against the wall 11 and also has the square end 20 to receive a key or crank (not shown in the drawing) wherewith the mechanism can be wound up.

Upon this shaft 18 is mounted the ratchet wheel 21 and the power gear 22, and the flat coil spring 23; all of which elements constitute the power plant of the apparatus and is arranged similar to, and operates similar to, the power plant of a clock which is well known in the art and need no detailed description here.

The spring 23 is made sufficiently strong to operate the mechanism and has one of its ends secured to the spacer 14 while its other end is operatively connected with the shaft 18 and the gear 22.

The gear 22 meshes with the pinion 24 on the intermediate shaft 25 which is journaled in the walls 10 and 11.

On this shaft 25 is mounted the gear 26 which meshes with the pinion 27 on the stop and start shaft 28 which is journaled in the walls 10 and 11.

On this shaft 28 is mounted the gear 29 which meshes with the pinion 30 on the second intermediate shaft 31 which is journaled in the walls 10 and 11.

On this shaft 31 is mounted the gear 32 which meshes with the pinion 33 on the governor shaft 34 which is journaled in the walls 10 and 11.

The governor 35, in this instance a vane

governor similar to the regulator in a clock, is secured to the shaft 34 and rotates therewith.

The gear 29 has the pins 36 projecting from one side thereof. The purpose of these pins will appear presently.

The stop and start lever 37 is hinged on the spacer 16 and has one end thereof projecting downward to within easy reach of the operator, while the other end thereof extends forward and has its extreme end formed into a hook 38 which is adapted to engage any one of the pins 36 when brought to the stop position shown in the drawing.

15 The gear 22 also meshes with the pinion 39 on the crank shaft 40 which is journaled in the walls 10 and 12.

On the outside of the wall 12, the shaft 40 carries the crank 41 which is provided with 20 the crank pin 42.

The oscillatory shaft 43 is journaled in the walls 10 and 12 and carries, on the outside of the wall 12, the crank 44 which is provided with the crank pin 45 and the 25 throw of which is larger than the throw of the crank 41. The shaft 43 also carries, on its other end, the block 46 from which the wiper or brush 47 is suspended through the bar 48.

30 The link 49 fits over the crank pins 42 and 45 and connects the cranks 41 and 44.

The holes 50 are provided for screws wherewith the apparatus may be fastened to the frame of the windshield.

35 The apparatus as a whole may be inclosed in a case, preferably of light weight construction.

The general operation of the power plant shown here is similar to the operation of 40 the power plant of a clock.

In order to prevent the spring from unwinding at a rate of speed too high for the purpose in hand, the governor mechanism is introduced and is operated by a train of 45 gears, although friction wheels, or other drive means may be employed, the object being to control the speed of the motive power release.

In the present instance, the vanes of the 50 governor revolve at a comparatively high rate of speed due to the high ratios between the gears and thereby limit the revolutions of the gear 22.

Since it is not necessary to operate this 55 apparatus continually, and since this apparatus should be wound up at all times and ready for immediate use, the stop and start mechanism is provided. The drawing shows the hook 38 of the lever 37 engaging one of the pins 36 whereby the entire mechanism is prevented from operating. If it is desired to start the mechanism, push the lever 60 65 in the direction of the arrow whereupon the hook 38 will disengage the pin 36 and the gears and shafts are free to rotate. The

lever 37 will remain in this start position, due to the weight of the overhanging arm, since this lever tends to find its equilibrium and rotates on the spacer sufficiently far to keep the hook 38 out of engagement with any of the pins 36. In order to stop the mechanism, push the lever 37 to the position shown in the drawing whereupon one of the pins will be caught in the hook 38 and further operation of the mechanism is arrested 75 and the spring 23 supplies sufficient force to hold the pin to the hook until the same is forcefully released from the pin to start the motor.

When this apparatus is in operation, the 80 shaft 40 is rotated by the pinion 39 and the crank 41 also rotates with the shaft 40. The rotation of the crank 41 produces a reciprocating motion in the link 49 which, in turn, produces an oscillatory motion in the crank 44 (due to its larger throw) and, consequently, a similar motion in the shaft 43 to which the crank 44 is secured.

85 This oscillatory motion of the shaft 43 produces a similar motion in the block 46 and, consequently, in the wiper or brush mechanism, causing the same to sweep back and forth over the glass 51 of the windshield 52 in an arcuate path 53.

90 It will be seen that the present invention provides an efficient, self-contained, and effective power unit, which can readily be applied, either temporarily or permanently, and which is convenient of control and a 95 convenient means of storing power for such purposes.

I claim:—

1. In an apparatus of the character described, the combination of, a housing open at both ends and at the top and at the bottom and comprising a rear wall perforated to reduce weight and to permit of access to the interior of this housing, a front wall perforated to reduce weight and to permit of access to the interior of said housing, a 100 sub-wall cut out to reduce weight and to permit of access to the interior of said housing, said sub-wall parallel with said rear wall and disposed back of and at one side of said front wall, spacers connecting said front wall to said rear wall, spacers connecting said sub-wall to said rear wall, spacers connecting said front wall to said sub-wall, a spring motor mounted between said rear and front walls, means for 105 operating a cleaning apparatus mounted on said sub-wall and said rear wall, and means for controlling the operation of said motor mounted in said rear and front walls. 110

2. In an apparatus of the character described, the combination of, a housing open at the ends and at the top and at the bottom and composed of a rear wall perforated to reduce weight and to permit of access to the interior of said apparatus, a front wall 115

perforated to reduce weight and to permit of access to the interior of said apparatus, a sub-wall cut out to reduce weight and to permit of access to the interior of said apparatus, said sub-wall parallel with said rear and front walls and disposed back of and at one side of said front wall, spacers connecting said front wall to said rear wall, spacers connecting said sub-wall to said rear wall, spacers connecting said front wall to said sub-wall, a power shaft journaled in said rear and front walls and actuated by a source of power, and means for operating a cleaning apparatus mounted on said sub-wall and said rear wall and operated by said power shaft.

3. In an apparatus of the character described, the combination of, a housing, a spring motor mounted in said housing, 20 means for operating a cleaning apparatus mounted in said housing and operated by said motor, a stop and start shaft journaled in said housing and operated by said motor, a stop and start wheel secured to said stop and start shaft and provided with stop pins projecting from one side thereof, and a stop and start lever hinged on said housing and comprising a handle portion extending downward and the lower end thereof projecting below the bottom of said housing, 25 said sub-wall parallel with said rear and front walls and disposed back of and at one side of said front wall, spacers connecting said front wall to said rear wall, spacers connecting said sub-wall to said rear wall, spacers connecting said front wall to said sub-wall, a power shaft journaled in said rear and front walls, a spring motor between said rear and front walls and operating said power shaft, a crank shaft journaled in said sub-wall and said rear wall and operated by said power shaft, a crank 30 on the front end of said crank shaft and disposed outside of said sub-wall, an oscillatory shaft journaled in said sub-wall and in said rear wall, a crank on the front end of said oscillatory shaft and disposed outside of said sub-wall and in alignment with the first said crank, a link connecting both of said cranks to reciprocally rotate said oscillatory shaft, a stop and start shaft journaled in said rear and front walls and operated by said power shaft, a stop and start wheel secured to said stop and start shaft and provided with stop pins projecting from one side thereof, and a stop and start lever hinged on one of said spacers and comprising a handle portion extending downward and the lower end thereof projecting below the bottom of said housing, an arm extending sidewise and provided with a hook to engage said pins, said stop and start lever locked in stop position by the action of said spring motor when said hook engages one of said pins, and said stop and start lever held in unlocking position by the weight of said arm when said hook is disengaged from said pins.

4. In an apparatus of the character described, the combination of, a housing open at both ends and at the top and at the bottom and comprising a rear wall perforated to reduce weight and to permit of access to the interior of this housing, a front wall perforated to reduce weight and to permit of access to the interior of said housing, a sub-wall cut out to reduce weight and to permit of access to the interior of said housing, said sub-wall parallel with said rear and front walls and disposed back of and at one side of said front wall, spacers connecting said front wall to said rear wall, spacers connecting said sub-wall to said rear wall, spacers connecting said front wall to said sub-wall, a power shaft journaled in said rear and front walls, a spring motor mounted between said rear and front walls, means for operating a cleaning apparatus mounted on said sub-wall and said rear wall, a power shaft journaled in said rear and front walls and actuated by said spring motor, a stop and start shaft journaled in said rear and front walls and operated by said power shaft, a stop and start wheel secured to said stop and start shaft, a stop and start wheel secured to said stop and start shaft and provided with stop pins projecting from one side thereof, and a stop and start lever hinged on one of said spacers and comprising a handle portion extending downward and the lower end thereof projecting below the bottom of said housing, an arm extending sidewise and provided with a hook to engage said pins, said stop and start lever locked in stop position by the action of said spring motor when said hook engages one of said pins, and said stop and start lever held in unlocking position by the weight of said arm when said hook is disengaged from said pins.
